INVENTOR

BY *Victor J. Evans*

ATTORNEY

UNITED STATES PATENT OFFICE.

OSCAR M. BLOOD, OF HERMAN, MINNESOTA.

DRAG.

Application filed November 27, 1922. Serial No. 603,543.

To all whom it may concern:

Be it known that I, OSCAR M. BLOOD, a citizen of the United States, residing at Herman, in the county of Grant and State 5 of Minnesota, have invented new and useful Improvements in Drags, of which the following is a specification.

This invention relates to road drags and 10 contemplates a construction wherein the dirt is moved sidewise toward the center of the drag, in a manner which prevents the dirt from running around the ends and leaving a ridge on either side of the center of the road, the drag being associated with a 15 leveler which follows the drag to equally distribute the dirt as will be readily understood.

In carrying out the invention I not only 20 provide a drag of novel construction, but design a leveler which in one position presents a smooth surface to the ground, which 25 surface is used when the dirt is in a dry condition, but which may be reversed to present a toothed surface to the ground when 30 the dirt is moistened thereby breaking up all large pieces of earth incident to the passage of the leveler over the ground.

The nature and advantages of the invention 35 will be better understood when the following detailed description is read in connection with the accompanying drawing, the invention residing in the construction, combination and arrangement of parts as 40 claimed.

In the drawings forming part of this 45 application, like numerals of reference indicate similar parts in the several views, and wherein:

Figure 1 is a plan view.

Figure 2 is a sectional view.

Figure 3 is a sectional view taken on the line 3—3 of Figure 1, looking in the direction of the arrow.

Figure 4 is a sectional view taken on the line 4—4 of Figure 3.

Referring to the drawings in detail, the drag essentially embodies a plurality of spaced parallel bars 10 which are connected together by angle bars in the formation of a frame. It is of course to be understood 50 that the frame may include any number of such parts with a view to varying its size and without departing from the spirit of the invention. The angle bars are of V-shaped 55 formation, and arranged in groups adjacent the opposed ends of the frame, the bars of

one group being indicated at 11, are reversely disposed with respect to the bars 12 of the other group. The horizontal frame portions of the respective bars are riveted or otherwise suitably secured to the bars 10, while attached to the depending portions 13 of said bars, are plates 14. These plates are manifestly of V-shaped formation to correspond to the configuration of the bars to 60 which they are secured, and the plates can vary in dimensions to space the frame a greater or less distance from the ground as desired. Arranged between the different groups of bars, is a plurality of straight 65 bars 15 which are also of angular formation in cross section, and each has secured thereto a plate 16 coextensive in length therewith. These bars 15 as above stated are 70 comparatively short bars and are arranged across the center of the frame in spaced parallel relation with the adjacent extremity of these bars overlapped. These bars and their plates are utilized to prevent ridges being formed in the center of the roadway 75 incident to the moving of the dirt toward the center by the particular configuration of the plates carried by the groups of bars 80 above described.

Arranged to follow the drag is what I 85 term a leveler, preferably made up of spaced members 18, and each member is secured to an angle bar 19 as clearly illustrated in Figure 4. The angle bars are connected together by transverse members 20 and also obliquely disposed members 21. Each member 90 18 has one smooth edge, and the corresponding edges of the members are arranged in juxtaposition, while the remaining longitudinal edge of each member is provided 95 with teeth 22. The follower in its entirety is adapted to be connected with the drag proper in any suitable manner which will permit the leveler to be converted, so that the smooth edges may be presented to the 100 ground, or the toothed edges so presented. When the leveler is used with dry earth the smooth edges are presented to the ground, but when the earth is wet, the toothed surface is presented so as to break up clods or 105 lumps of dirt as the leveler is moved over the surface.

While it is believed that from the foregoing description, the nature and advantages of the invention will be readily apparent, I 110 desire to have it understood that I do not limit myself to what is herein shown and de-

scribed, and that such changes may be resorted to when desired as fall within the scope of what is claimed.

Having thus described the invention, I claim:

1. A road drag comprising a frame, road engaging elements arranged in groups at the opposed ends of the frame, said elements being of angular formation, with one group 10 reversely disposed with relation to the other group.
2. A road drag comprising a frame, road engaging elements supported by the frame, each element being of substantially V- 15 shaped formation, said elements being arranged in groups adjacent the opposed ends of the frame, with one group reversely disposed with relation to the other group.
3. A road drag comprising a frame, road 20 engaging elements arranged in groups adjacent the opposed ends of the frame, said elements being of V-shaped formation in plan, with the elements of one group reversely disposed with respect to those of the other group, and additional road engaging 25 elements arranged between said groups in spaced parallel relation, and with the adjacent edges of the latter mentioned element overlapped.
4. A road drag comprising a plurality of 30 spaced parallel bars, and angle bars of V-shaped formation arranged at one side of the parallel bars and connecting the latter, a road engaging element secured to each angle bar and corresponding in shape therewith, said angle bars and plates being arranged in groups adjacent the ends of the 35

drag with one group reversely disposed with respect to the other group, additional bars arranged between said groups in spaced parallel relation and connected to the first mentioned bars, and road engaging elements carried by said additional bars for the purpose specified. 40

5. A road drag comprising a frame, a plurality of road engaging elements arranged in groups adjacent the ends of the frame, said elements being designed and arranged to move the dirt sidewise toward the center of the road, additional elements arranged between the groups for spreading the dirt moved toward the center, and a leveler connected with the drag at the rear of the latter for the purpose specified. 45

6. A road drag comprising a frame, road engaging elements arranged in groups at the opposed ends of the frame, said elements being designed and arranged to prevent the dirt from running around the ends of the drag, and moving the dirt toward the center of the road, additional road engaging elements arranged between the groups and designed to spread the dirt so moved toward the center, a leveler arranged at the rear of the drag and including spaced parallel members, each member having a smooth edge, 50 and a toothed edge, and means for connecting the leveler with the drag whereby said leveler may be converted to present either of said edges to the ground for the purpose 55 specified. 60

In testimony whereof I affix my signature.

OSCAR M. BLOOD.
